COIN CONTROL UNIT

Joseph W. Srodulski, Chicago, Ill.

Application September 20, 1937, Serial No. 164,660

4 Claims. (Cl. 194—102)

This invention pertains to coin operated devices and has as one of its important objects the provision of a coin control unit for use with various types of vending and service machines 5 adapted for operation upon the insertion therein of a proper coin or check.

It is a further object to provide a compact control unit including a manual operating lever, a drive member, and an overload clutch between 10 the manual member and operating member to prevent forcing the device.

It is a further object to provide novel latching means in such a control unit and adapted to lock the operating member or plate against 15 movement.

It is another object to provide a control unit adapted for use with a coin or check selector cooperable with the latching means to free the operating or driving plate for movement by the 20 manual operating lever.

It is another object to provide means for maintaining the latching mechanism in released condition until a full stroke of the operating lever 25 is made.

Still another object is the provision of a combination coin elevator and secondary locking means adapted to receive approved coins or checks from the main selector and release certain secondary or auxiliary latching mechanism 30 and elevate the approved check or coin for further selective disposition.

Yet another object is the provision of improved scavenger means disposed between the 35 coin entrance opening and the principal selector for trapping debris such as match sticks, cardboard wafers, etc., the scavenger being further adapted to obviate the gathering of grease and other forms of soil which tend to accumulate 40 from the continuous passage of coins and tokens.

Additional objects and novel features of construction and operation of the improved control unit will appear as the following description develops in view of the drawings in which:

45 Fig. 1 is a side elevation of the complete unit showing the mounting head and side plate;

Fig. 2 is a top plan view with part of the mounting head cut away and is taken along the 50 irregular line 2—2 of Fig. 1;

Fig. 3 is a fragmentary vertical elevation through the unit along the irregular line 3—3 of Fig. 2, showing the opposite side of the side plate of Fig. 1 in elevation;

55 Fig. 4 is a fragmentary vertical section through

the mounting head along lines 4—4 of Fig. 2 and showing the overload clutch in elevation;

Fig. 5 is a rear elevation of the unit looking in the direction of lines 5—5 of Fig. 1;

Fig. 6 is a vertical section through the unit 5 as viewed in the direction of lines 6—6 of Fig. 2, showing particularly portions of the scavenger, selector unit and coin elevating means;

Fig. 7 is a vertical section viewing the coin elevating means from the rear along lines 7—7 10 of Fig. 6;

Fig. 8 is a fragmentary front vertical section through the mounting head and clutch as seen along the irregular line 8—8 of Fig. 6;

Fig. 9 is a vertical median section through the 15 scavenger as taken along lines 9—9 of Fig. 2;

Fig. 10 is a fragmentary vertical section through the main selector and selective coin passages therefrom, as viewed in the direction of 20 lines 10—10 of Fig. 6;

Fig. 11 is an angular section through the scavenger along lines 11—11 of Fig. 6.

The improved control unit, which is the subject of the present invention, is intended for use on vending machines, automatic phonographs, 25 amusement apparatus, and in fact any type of device which may be operated by a coin control. The novel unit, moreover, is intended for use with a variety of coin and token selecting devices, and is especially suited for use with a type 30 of selector or tester described and claimed in United States Patent 2,073,392 for improvements in an Adjustable check testing apparatus. This latter type of selector, it may be observed, may be utilized to test and select coins having a predetermined surface configuration, such as the "buffalo" nickel, and in addition will pass certain type of checks or tokens, while rejecting other coin elements for which it is not adjusted. It is to be understood that other forms of testing device may be used, the invention being of 40 especial utility where the testing device will accept both coins and tokens of predetermined character.

As viewed in Fig. 1 herein, the present control 45 unit in one of its preferred forms, includes a mounting head or casing 14 having a hollow protuberance or flare 15 and a marginal mounting flange 16 adapted to fit flush against a cabinet structure or the like. In the upper region 50 of the protuberance (Fig. 6) there is provided a coin entrance 17 into which a coin is deposited for transit through a scavenger later to be described, and into the principal selector for testing it.

Extending across the hollow portion of the mounting head (Figs. 2, 6 and 8) is a handle shaft 18 seated in suitable bosses formed in the casting and having an end portion attached by pin means with an operating lever 19. Keyed to the handle shaft 18 within the mounting head is an overload clutch generally indicated at 20 and of especial design to be described hereafter in detail.

10 A side plate or section 21 (Figs. 1 and 3, particularly) is extended from within the mounting head, being removably attached to the latter by means such as the screws 22 and providing a principal support for the operating or drive plate 15 and part of the latching mechanism.

15 This side plate 21 has a lower laterally curved apron 23 (Fig. 3) which inclines toward the opposite side of the mounting head and terminates opposite a small integral wall formation 24 extending from the opposite side of the mounting head in such manner as to provide a reject coin passage 25 descending toward the lower front portion of the mounting head and terminating in a small reject cup or chamber 26 accessible 20 through a front opening 27 to the operator, so that he may retrieve rejected coins therefrom.

20 The principal operating member, which is actuated by the handle 19 when the proper coin is deposited, is termed for convenience herein a drive or operating plate 28 slidably mounted on the inner surface of the side wall plate 21 (Fig. 3) and having a rearward nose or extension 29 adapted for operative engagement with some instrumentation under the control of the unit, such 30 for example as a merchandise dispensing control or operating lever.

25 The drive plate 28 is provided with two horizontally extensive and parallel slots 30 and 31, and through which protrude offset riding studs 32 and 33 respectively, there being a stud shaft 34 extended through the upper slot from the side plate across to the coin chute or elevator and serving not only as a partial support for the latter and a partial sliding support for the drive 35 plate, but also as a mounting shaft for part of the coin elevating mechanism hereinafter to be described.

30 Along its upper edge the drive plate has an ear 35 on which is hooked one end of a spring 36 secured at its opposite end to an ear 37 on the side wall plate 21, this spring being adapted to urge the drive plate (toward the right, Fig. 3) into a normal position.

35 At the right-hand extremity of the drive plate 55 is a lateral flange 38 (Figs. 3 and 4) normally bearing against a roller 39 carried on an arm of a member of the clutch unit 20, such that when the lever 19 is depressed upon deposit of a proper coin, the clutch roller 39 will urge the 40 drive plate toward the left against the tension of spring 36.

45 Along its lower edge the drive plate 28 has a number of spaced notches 40-41 and smaller intervening notches 42 for engagement by a full stroke dog 43 having a safety latch operating extension or arm 44, the purposes of which will later appear. The full stroke dog 43 is normally positioned by a spring 45, as seen in Fig. 3, and, in addition to other functions, prevents return 50 movement of the drive plate until the latter has made a complete operating stroke toward the left. As the plate shifts toward the left, the shorter arm of the dog 43 pivots in an anticlockwise sense, its nose riding into the smaller slots 75 42 which are too shallow to permit the dog to

5 pivot clockwise if an attempt be made to restore the slide before the full stroke has been made; however, when the full stroke is made the smaller arm of the dog 43 will ride into the terminal slot 40 which is large enough to permit the dog to 5 pivot in either direction. Upon the return stroke, the dog will ride in and out of the notches 42 but pivoting in a clockwise sense until it reaches the opposite end slot 41.

10 Pivotedly mounted on a lateral ear 46 on the side plate 21 is the main latch dog 47 having an end portion 48 normally protruding through a slot in the side wall plate (Figs. 1, 3 and 5) and having an ear 49 normally disposed in the path of movement of an edge portion 50 of the drive 15 plate so as to prevent movement of the latter completely toward the left, there being, however, normally a space between the edge 50 and the locking dog so that the drive plate may be reciprocated a limited amount in its idle stroke 20 movement for operation of certain selector mechanism which includes a vertically reciprocable selecting operating arm 51 having an elongated slot 52 slidably embracing a stud 53 on the side wall plate 21 and having a cam roller stud 54 25 at its upper end (Figs. 1 and 3), which roller is disposed in an arcuate cam slot 55 extending upwardly from the lower horizontal riding slot 31 in the drive plate in such manner that when the latter is moved toward the left the roller 54 30 is cammed downwardly and will operate certain selecting or testing mechanism shortly to be described. The stud roller 54 protrudes through a vertically extensive opening 68 in the plate 21 35 to limit the movement of the reciprocable arm 51. An idle guide arm 56 is attached at its left-hand end to the reciprocating arm 51 and the roller means 54 thereon and at its opposite end to the guiding or riding stud 23 and serves to effect linear movement of the operating arm 51 when 40 the same is cammed by movement of the drive plate.

45 In the present embodiment a selector or testing cartridge or unit 57 is installed in the central region of the control unit and is of the type 45 shown in Fig. 11 of the United States patent hereinbefore mentioned, and this unit includes a depending and vertically reciprocable operating arm 58 (Fig. 5 herein; also identified at 65 in Fig. 11 of the aforesaid patent), and this operating member 58 is connected by a pin 59 to a lower portion of the operating arm 51 in such manner that when the drive plate 28 is reciprocated the selector operating arm 58 is likewise reciprocated, and it should be observed that the 55 idle stroke movement of the drive plate is sufficient to actuate the testing device so that a previously deposited coin will be approved or rejected by the selector and caused to pass therefrom toward the reject passage 25 or the elevator passage 60 (Fig. 10) depending upon which way a pivoted selector element or gate 62a in the testing device 57 moves the coin after performing its testing operation.

50 The main latch dog 47 has a lateral pin 61 65 (Fig. 3) which extends into the testing unit 57 and there engages a trip arm 62, which is released and moved by the testing mechanism (when a proper coin or special check is received in the latter) responsive to the movement of 70 the operating member 58 of the testing unit, and is effective to pivot the dog 47 toward the left into the dotted line position shown in Fig. 5 so as to dispose the ear 49 on the dog out of the path of movement of the edge portion 50 on the 75

drive plate (Fig. 3), thus permitting the latter to continue toward its full stroke position.

In addition to the full stroke dog 43 (Fig. 3) and its partial function of preventing return movement of the drive plate after the latter has been displaced a predetermined amount toward its operative or full stroke position, there is provided a safety or full stroke latch 63 (Fig. 1) pivoted on the side wall plate 21 as at 64 and having an offset arm 65 protruding inwardly through a slot 66 in the wall plate for engagement by the arm 44 on the full stroke dog 43 when the latter is pivoted in a clockwise direction upon the return movement of the drive plate after the upper end of the dog has moved into the notch 40 on the plate in such manner that the safety latch is pivoted in an anti-clockwise direction (Fig. 1) so as to raise the latching end 63 thereof out of the way of the end 48 of the main latching dog 47.

Normally the safety latch is positioned by gravity as seen in Fig. 1, with the arm 63 bearing down against the angled edge 48 of the dog 47 so as to fall into latching position in a notch 48' formed in the dog between the end portion 48 and the ear 49, so that once the latch dog has been pivoted into released or non-blocking position by operation of the testing mechanism, the safety or full stroke latch 63 falls by gravity into the notch 48' and will prevent return movement of the main dog into latching position until the drive plate has made its full stroke and the full stroke dog 43 (Fig. 3) is pivoted in a clockwise direction by the return movement of the drive plate. This return movement causes the arm 44 of the full stroke dog to engage the lower offset end 65 of the full stroke arm so as to pivot the latter in an anti-clockwise direction (Fig. 1) and position the same completely out of the path of the dog 47 so that the latter may return to its normal latching position. A guide bracket 67 (Fig. 1) guides the movement of the arm 63 relative to the dog 47.

A secondary testing or selecting means is provided in the form of a vertical chute 69 (Figs. 1, 5 and 6) having communication at its lower end with the coin passage 60 into which coins are discharged from the testing device 57. This vertical chute 69 provides a path of determined length having a discharge opening 70 at its upper end for checks or tokens and a selecting kick-out opening 71 between its ends and below the top discharge opening or terminal 70. This secondary selecting mechanism includes coin elevating means in the form of a vertically reciprocable elevator rod 72 (Figs. 1 and 7 particularly) pivotally attached as at 73 (Figs. 3 and 5) at its upper end to an eccentric portion of a rocker or yoke 74 which in turn is pivotally mounted on a cross stud 34 which extends from one end laterally of the side plate 21 and at its opposite end is attached by means of the screw 34' to the upper end of the secondary chute member 69. The yoke member 74 has its yoke or bifurcated portion 75 embracing a lateral stud 76 attached to the drive plate 28. Thus, when the drive plate is reciprocated, the elevating rod 72 will likewise be reciprocated through the rocking action of the yoke 74.

At its lower end the elevating member 72 has an offset lateral extension 77 (Fig. 7) in a corner of which is provided a coin engaging notch 78 adapted to fit against the lower edge of a coin received in the chute passage from the discharge chute 60. This lateral extension rides in a ver-

tical slot 79 formed in the side of the chute, and the pivotal mounting 73 at the upper end of the rod 72 is sufficiently loose to permit sidewise play of the rod in a direction to dispose the extension 77 inwardly and outwardly of the vertical slot 79. 5

A spring urged presser arm 80 movable on a pin 81 bears against the lower portion of the rod 72 and normally urges the latter to dispose its offset coin engaging extension 77 into the chute passage so as to engage a coin moving into the latter. However, there is provided (Fig. 5) on the side of the chute 69 a lower cam lug 82 which is engaged by the lower end portion of the rod 72 (Fig. 1) when the latter is in its normal lowered position in such manner as to urge the lower end of the rod 72 partially out of the chute, leaving, however, enough of the extension 77 therein to engage a coin, should one enter the chute. A second or blocking cam lug 84 extends from the side of the chute above the lower cam lug 82, 20 and if there is no coin resting on the coin receiving notch 78, the idle stroke movement of the drive plate will move the elevator rod 72 upwardly a distance sufficient to cause the lower end portion of the rod to disengage the lower cam lug 82, whereupon the presser arm 80 will urge the elevator rod toward the chute so that a lateral extension 83 formed on the rod 72 abuts the upper cam member 84 and thus prevents further upward movement of the elevating rod 30 and consequently further movement of the drive plate. Thus, there is afforded a second latching mechanism which would be effective to prevent operation of the control even though the selector or tester 57 were omitted. 35

When a proper coin is discharged from the testing device 57 into the chute 60, such coin will rest in the notch 78 on the elevator rod extension, and this notch is of a depth calculated to hold the elevator rod 72 outwardly of the chute against the spring 80 as the rod moves upwardly in such manner that the projecting stop finger 83 on the rod will miss the upper blocking lug 84 and cause the finger to ride on a cam portion 84' so that the extension 77 is substantially wholly withdrawn from the chute passage. When such a coin has been elevated to a predetermined position, a spring presser finger 85 (Figs. 6 and 7) on the opposite side of the chute will project its nose portion beneath the coin and prevent its dropping down when the elevator recedes. Thus, the coins may be moved in step by step fashion toward the upper end of the chute, those of a predetermined diameter being urged out the intermediate drop-out opening 71 by operation of a second presser finger 85' (Fig. 1) on the opposite side of the chute, and the other larger-diameter checks continuing on toward the top discharge opening 70. 50 55

Not only are coins selected as to diameter by this secondary selecting means, but they are also tested to an extent as to thickness by virtue of the calculated depth of the notch 78 in the elevator extension 77, it being apparent that should a coin be too thin, the rod 72 would not be wedged outwardly far enough to miss the upper blocking lug 84. A further advantage in the arrangement of the secondary selector and elevator resides in the fact that the unit is rendered more compact for certain types of installation where 70 the space into which the unit fits is of a depth substantially equal to the height of the unit, so that coin receiving drawers may be arranged between the limits of this depth, certain coins discharging from substantially the central region 75

of the vertical chute passage so that they may gravitate into one receptacle, while other checks discharge from the top of the chute and likewise may gravitate into another receptacle.

5 A novel form of scavenger is utilized to conduct the deposited coins from the entrance opening 17 into the receiving opening 51' of the primary or main selector. The scavenger includes a pair of complementary side plates 86 and 87 (Figs. 2, 6, 10 9 and 11), each having an outwardly flared lip 88 at its upward end positioned below the deposit opening 17. The plate 86 is stationary and attached to the unit structure by an offset ear 89 and bolt means therefor. The plate 86 also has 15 an edge portion bent over at right angles to provide a mounting flange 90 with upset ears 91 providing a mounting for the companion plate 87, the latter having a pair of spaced offset ears 92 aligned with the ears 91 and through all of 20 which is passed a pin 93 providing the pivotal axis for the companion or movable scavenger plate 87.

The plate 86 has a pair of spaced parallel ribs 94 disposed and spaced substantially away from 25 the locus of the center of a coin moving downwardly on offset ledge 95 on the companion plate, while this latter or companion plate has a single rib 96 disposed parallel to and between the ribs 94 and extending substantially along the locus 30 of the center of a descending coin. This arrangement of ribs assures that a deposited coin will always traverse the scavenger and reach the testing device 51 regardless of the possible collection of soil on the sides of the scavenger 35 plates, it being commonly known that such soil tends to collect on the sides of chute passages as a result of the continuous movement of coins therein and can obstruct the free movement of the coins. This latter arrangement of ribs, however, obviates operating troubles from this source.

The movable or companion scavenger plate 87 is normally disposed by gravity with the coin ledge or flange 95 close against the stationary plate. In order to open the scavenger there is 45 provided a push button 97 (Figs. 2 and 6) in a side of the casing head 15 and having an inner end portion adapted to bear against an ear 97' on the movable scavenger plate 87, such that when the button is pushed inwardly the movable 50 scavenger plate is pivoted away from the stationary plate, and debris, such as match sticks, paper, defective coin elements, and the like, will gravitate therefrom downwardly over the inclined apron portion 23 and into the reject opening 26, the scavenger again gravitating into closed position when the button 97 is released.

In order to prevent fraudulent operation of the device by forcing the handle 19, there is provided a novel overload clutch 20 shown in Figs. 2, 4 60 and 8. This clutch includes a substantially annular plate 98 (Fig. 4) having a collar 99 movably embracing handle shaft 18. On a depending ear of this floating clutch member is the roller 39 which engages the lateral offset 38 on the 65 drive plate to move the latter.

Pivotedly mounted as at 100 on the floating plate or disc 98 is a yoke arm 101 having its opposite free end 102 disposed substantially opposite the pivotal mounting 100 thereof and both 70 the latter and the end 102 lying along a diameter through the shaft 18 and plate 98. A spring 103 has one end attached to an offset ear 104 on the free end 102 of the yoke, the other end of this spring being anchored on an ear 105 struck up 75 from the floating plate 98. Thus, the yoke arm

100 is urged in an anticlockwise direction as seen in Fig. 4, this movement being limited by means of a pin 106 anchored in the plate 98 and riding in an arcuate slot 107 in the arm 101.

5 Formed between the ends of the yoke member 101 is an inwardly extending lug 108 having a graduated and substantially circumferentially extending edge 109 which is normally seated in a complementary slot 110 formed in a driven annulus 111 keyed for rotation with the handle 10 shaft 18 by means of a collar 112 (Fig. 8) having a reduced and squared shoulder 113 which fits into a correspondingly squared opening in the annulus so that the latter of necessity must turn with the collar 112, the latter turning with the 15 shaft 18 by virtue of a pin 114 extending through the same into the shaft.

An examination of Fig. 4 will disclose that if a force is applied to the lever 19 to move the latter downwardly (clockwise), the shaft 18 will 20 rotate the moving disc or annulus 111 and cause the side portion 115 to bear against the yoke lug 109. The slot edge 115 has a very slight camming slant and when adequate force is applied to the lever 19, the camming engagement of the moving disc with the yoke lug will urge the yoke against the tension of spring 103 and cause the withdrawal of the yoke lug from the slot 110, so that the handle and shaft will suddenly be freed from the resistance of the floating clutch 30 member in the bearing engagement of its roller 39 against the drive plate, and the latter can in no way be injured or forced against its latching means. As soon as the handle 19 is restored to the normal position of Fig. 4, the spring 103 will 35 again cause the yoke lug 109 to slip back into the notch 110 in the moving clutch disc.

The novel control unit will thus appear to provide a manual operating lever and a driven member or plate with an overload clutch interposed 40 between the handle and plate, together with detent latching means for preventing the normal movement of the plate by the handle member, this detent means being released by operation of a primary coin testing device, and there further 45 being provided a secondary selecting mechanism and a latch rod and elevator for preventing movement of the driven plate unless a coin of predetermined character is received from the primary selector. The secondary selector in addition to 50 unlatching the drive plate also moves the coins or checks along a determined path provided by the chute and causes coins of one kind to be discharged at one point, and coins of another kind to be discharged at a different point. In 55 addition, the invention provides a unitary structure including a casing head of novel construction, an improved form of scavenger for conducting coins from the casing head to the primary selector, and a novel form of overload clutch. 60

Operation

In operating the device, a coin or token may be inserted through the coin depository 17 (Figs. 6 and 8), whereupon the handle 19 is pulled 65 downwardly, causing the roller 39 (Fig. 3) to bear against the lateral flange 38 on the main drive plate 28, thus urging the latter toward the left. It may be remarked here that the driving connection between the handle 19 and the roller 70 39 is effected through the overload clutch mechanism generally indicated at 20 (Fig. 4).

As the drive plate 28 shifts to the left, the cam edge portion 55 of the lower horizontal slot 31 bears down on the roller 54, depressing the 75

rod 51 and consequently depressing the test operating rod 58 so as to actuate the primary testing means 57.

If the coin be a proper one, the testing device 5 will cause the dog 47 to pivot outwardly or to the left (Fig. 5) through connection of the pin means 61 from the testing device with the short offset arm portion of the dog 47.

When the dog 47 moves to the left as aforesaid, the ear 69 thereof is removed from the path of the lower edge 50 of the main drive plate (Figs. 3 and 5) so that the latter may continue its operative movement under urging of the handle 19, and at substantially the same time the safety latch dog 63 (Fig. 1) drops to block the portion 48' of the dog 47 to prevent return of the latter to latching position until the drive plate has made its full inward or operating stroke.

20 There is sufficient idle stroke or "free play" movement in the main drive plate mechanism for operation of the primary testing arm 51 and the operation of the testing device 57 is so rapid that by the time the testing operation is 25 complete and the coin either rejected or accepted, the coin, if it be accepted, will have gravitated down the short ramp 60 (Fig. 6) and onto the notched elevator ear 78 (Fig. 7) so that continued operation of the handle 19 will effect a 30 raising movement of the elevator and, assuming the coin to be of a proper thickness so as to cam the elevator rod outwardly to permit the lug 83 to miss the stopping lug 84 (Fig. 1), the drive plate may make a complete inward movement due 35 to the release of the latch dog 47 and the release and upward movement of the elevator, the latter having a connection through the yoke 74 (Fig. 3) and a pin 76 on the drive plate to block movement of the latter in the event the elevator is 40 not raised.

Thus, the primary and secondary testing means are released by the same coin, which is effective to permit free movement of the drive plate completely to the left.

45 When the drive plate moves toward the left as aforesaid, the full stroke dog 43 (Fig. 3) will pivot in an anticlockwise direction and ride in and out of the smaller notches 42 until the larger right-hand release notch 40 is reached and the 50 drive plate starts back to normal position under urging of the spring 36. This latter movement causes the dog 43 to pivot in a clockwise direction in and out of the smaller notches 42 so as to cause the lower arm 44 thereof to bear against the offset ear 65 of the safety latch 63 (Fig. 1 55 also) and pivot the latter out of blocking position relative to the main latch arm 47, thus permitting the latter to be restored to its latching position for instant engagement with the end 50 of the drive plate the moment the latter returns to its normal position.

Meanwhile, previously deposited coins in the chute 69 (as in dotted lines, Fig. 6) will be elevated in steps with each subsequent operation of the handle 19 and lodgement of a new coin on the elevator coin seating notch 78.

70 The device is intended to be used with minted coins and also with special tokens, the tokens having a diameter different from that of the coins and coin elements raised by the elevator passing out the upper mouth 70 of the chute if they are of one diameter, while the coin elements of less diameter are separated out by passing through the sidewise discharge opening 71 under urging of the presser finger 85'.

While the novel features of the control unit have been described herein with particularity, it is to be understood that various changes may be effected in the same without departing from the spirit of the invention, and the appended claims are intended to include within their scope all forms of modification, rearrangement and the like fairly coming within the spirit of the invention.

Having thus described my invention, what I 10 claim as new and desire to protect by Letters Patent is:

1. A latching and coin selecting attachment for use with coin-free control devices having operating mechanism, said attachment including a 15 body providing a coin passage having a receiving end and a discharge end and a sidewise drop-out opening between said ends and through which coins of less than a determined diameter may pass, a coin moving member mounted on said 20 body for reciprocable movement relative to the ends of the passage and also for movement laterally thereof and having a blocking formation and an offset extension projecting into said passage near an end thereof, said offset extension 25 having a notch for engaging a coin along its edge and an adjoining side of the coin whereby said rod may be moved laterally of the passage dependent on the thickness of the coin so engaged, spring means normally urging said coin moving member and extension toward the passage, cam means engaged by said coin moving member in its normal position to move said extension in a direction out of the passage for engagement of a coin in said notch, and blocking 30 means arranged on said body and effective to engage said blocking formation to prevent effective movement of said coin moving member unless the same is moved outwardly of said passage by a coin in said notch portion a distance 35 sufficient for said extension to clear said blocking formation, said coin moving member being arranged for reciprocation by said operating mechanism.

2. Selector mechanism for coin-controlled devices, said mechanism including a body providing a coin passage having receiving and discharge ends and a drop-out opening of determined width between said ends, yieldable finger means extending into said passage for preventing movement of 45 coins toward said receiving end, and a reciprocable coin shifter on said body and having an extension projecting into said passage to engage a coin at said receiving end, a blocking member on said body and normally engaged by 50 means on said shifter to prevent effective movement thereof, said shifter extension being arranged to engage the side portion of a coin at 55 said receiving end to move said shifter for clearance of said blocking member to permit effective 60 movement of the shifter, the latter being adapted for operative reciprocation by operating means in said coin-controlled device.

3. A coin selecting device including means providing a coin passage having an entrance and an 65 exit and a discharge opening therebetween and through which a coin element of certain size moving along said passage may pass before reaching said exit, mechanism operable to move coin elements in series from said entrance toward 70 said exit, means normally blocking effective movement of said coin moving mechanism, said coin moving mechanism including coin-engaging means arranged to shift said coin moving mechanism so that it will not engage said block- 75

ing means when a coin element engaged thereby is of a certain size.

4. Mechanism for testing and selecting coin elements according to size, said mechanism comprising means providing a coin passage having an entrance and a plurality of exits toward which coin elements are moved in series from said entrance, a coin moving member mounted for movement back and forth in a direction from said entrance toward said exits and also for shifting movement in a direction laterally of said passage, means yieldingly urging said coin moving member laterally toward said passage, means limiting the movement of the coin moving mem-

ber toward said passage so as to leave a space in which a coin element may lodge between the coin moving member and the passage, means providing a blocking member engaged by said coin moving member to prevent movement of the same and a coin element engaged thereby toward said exits, coin elements of predetermined size being effective to move the coin moving member away from said passage and out of the path of said blocking member for effective operation to move said coin element toward said exits.
